DESIGN FOR A LIPSTICK HOLDER

Elsa Schiaparelli, Paris, France

Application November 17, 1937, Serial No. 72,952

Term of patent 14 years

To all whom it may concern:

Be it known that I, Elsa Schiaparelli, a citizen of the Republic of France, residing in the city of Paris and Republic of France, have invented a new, original, and ornamental Design for a Lipstick Holder, of which the following is a specification, reference being had to the accompanying drawing, forming a part thereof.

In the drawing:—

Fig. 1 is a front elevational view of a lipstick holder in closed position showing my new design.

Fig. 2 is a front elevational view thereof on a slightly smaller scale and in open position with the lipstick compartment separated from the holder.

The holder is round in cross-section and is transparent and the reverse side is substantially like the side shown.

I claim:—

The ornamental design for a lipstick holder as shown and described.

ELSA SCHIAPARELLI.
